UNITED STATES PATENT OFFICE.

CHARLES B. DOOLIN, OF SAN ANTONIO, TEXAS.

LIQUID MEASURE AND STRAINER.

1,261,495.

Specification of Letters Patent. Patented Apr. 2, 1918.

Application filed April 14, 1917; Serial No. 162,171.

To all whom it may concern:

Be it known that I, CHARLES B. DOOLIN, a citizen of the United States, residing at San Antonio, in the county of Bexar and 5 State of Texas, have invented certain new and useful Improvements in Liquid Measures and Strainers; of which the following is a specification.

This invention relates to devices for measuring and straining liquids and discharging them into a receptacle or tank without exposing the liquids after being strained to the atmosphere or rendering the liquid liable to be deteriorated by dust or other foreign matter.

With these and other objects in view, the invention consists in certain novel features of construction, as hereinafter shown and described and then specifically pointed out 20 in the claims; and in the drawings illustrative of the preferred embodiment of the invention.

Figure 1 is a vertical section of the improved device.

Fig. 2 is a transverse section on the line 2—2 of Fig. 1.

Fig. 3 is a view similar to Fig. 1 illustrating a modification in the construction.

The improved device comprises a measuring can represented as a whole at 10 and of any suitable size or capacity. The member 10 is preferably formed with an outwardly flaring upper end 11 and provided with a suitable lifting handle 12 at one side. Located within the body 10 and spaced from its lower end is a downwardly directed conical diaphragm or partition 13 having a discharge opening at its lowest point, from which a discharge conduit 14 leads laterally through one of the side walls of the receptacle as shown at 15. The conduit 14 extends beyond the outer face of the casing and is provided with a nipple 16 adapted to receive a section of hose 17. At its free 45 end the hose member is provided with a discharge nozzle 18, preferably reduced at its free end.

Attached to the side of the casing 10 is a catch device 19 to receive and support the hose member when in its upper or inoperative position, as shown in Fig. 1. The catch device 19 is preferably of resilient material and clasps the hose with sufficient grip to hold it in place from displacement 55 when not in use, but will readily yield when

sufficient force is applied to withdraw the hose.

Surrounding the opening of the member 13 is a valve seat represented at 20, which is secured in any suitable manner to the upper face of the diaphragm 13. Engaging the seat 20 is a flat valve 21, of yielding material such as leather or hard rubber, and extending vertically from the valve is a lifting stem 22. Connected to the upper face of the member 13 and spaced above the valve seat 20 is a screen device represented as a whole at 23, and preferably formed of suitable fabric material adapted to effectually screen oil or other liquids and extract therefrom particles of foreign matter. The screen material may be fine mesh-wire, or other suitable filtering material, depending upon the oil or other liquid which is to be screened. If gasoline is the liquid which is to be measured, and screened, the material 23 may be buck-skin or the like usually employed for screening gasoline before it is deposited in the tanks of automobiles.

A metal disk 24 is arranged centrally of the screen and to which the latter is attached, the member 24 being perforated to permit the stem 22 to slidably move therethrough. At its outer edge the screen member is provided with an annular frame or ring 25 to which the screen material is attached at its outer edge while the frame member 25 is riveted or otherwise secured to the member 13. An annular holding member 26 is applied to the under-face of the screen material where it engages the central disk 24 to still further secure and support the screen material. Bearing over the upper face of the screen material and its frame 25 is a bearing 27 having a central perforation through which the stem 22 passes. A supporting bracket 28 is connected at its ends to the member 27 and is perforated at its center to permit the stem 22 to pass through.

A spring 29 is located between the valve 21 and the plate 24 to hold the valve 21 yieldably in position upon its seat 20.

Attached to the inner face of the receptacle 10 near its upper end is a bracket 30 to which a bell-crank lever member 31 is pivoted at 32. The member 31 is coupled at its inner end to the stem 22 by a rod 33. At its outer end the member 31 terminates

in an enlargement 34 to receive the thumb of the operator when he grasps the handle 12 by the fingers of one hand. The receptacle 10 above the diaphragm 13 will preferably be provided with annular beads 35 gaged to indicate the quarts, pints, gallons or other measures.

In Fig. 3 a modification in the construction is shown, consisting in forming the outlet 14 shorter than shown in Fig. 1 and forming a relatively large opening 36 in the side of the shell 10 below the diaphragm 13 to enable the hose 17 to be attached, the hose connection being disposed entirely within the shell 10. In the modified structure a hood or smaller shell 37 is disposed within the larger shell and attached by its lower edge to the diaphragm 13 and inclosing the valve 21. The hood 37 is provided with a plurality of relatively large openings 38 in its lower portion and provided with a detachable cap 39 at its upper end, the latter provided with an aperture through which the stem 22 extends. The screen 23 is centrally apertured to receive the hood 37. The spring 29 operates at its upper end against the lower face of the cap 39. A supporting ring or flange 40 encircles the hood 37 and is attached thereto and operates to support the screen material, the ring 40 thus serving the same purpose as the ring 26 in the structure shown in Fig. 1.

It will be obvious that with a device constructed as shown when a certain predetermined quantity of liquid is required, for instance, oil to be furnished to the oil reservoir of an automobile, the desired quantity is run into the receptacle 10 and the nozzle 18 connected into the receiving aperture of the reservoir or other receiver and held in position with one hand while the receptacle is engaged by the handle 12 with the other hand. The operator then presses downwardly upon the terminal 34 of the operating bell-crank with the result of releasing the valve 21 and permitting the contents of the receptacle to flow through the hose into the reservoir or other receiver, the oil or other liquid being strained by passing through the screen device 23.

The improved device may be of any required material or of any required size or capacity.

Having thus described the invention, what is claimed as new is:

1. A device of the class described comprising a receptacle having a conical diaphragm provided with a discharge and a valve seat surrounding the discharge, a valve engaging said seat and having an upwardly directed stem, an annular screen member supported at its outer edge upon the diaphragm and spaced above the valve seat, a central sup-

port connected to the inner edge of the screen and provided with a guide aperture 65 to receive the valve stem, and a stay bar extending over the central support and connected thereto and to the diaphragm.

2. A device of the class described comprising a receptacle having a transverse dia- 70 phragm provided with a discharge and a valve seat surrounding the discharge, a valve engaging said seat and having an upwardly directed stem, a supporting ring engaging said diaphragm, an annular screen member 75 supported at its outer edge by said ring and spaced above the valve seat, a central support connected to the inner edge of the screen and provided with a guide aperture to receive the valve stem, and a stay bar 80 extending over the central support and connected thereto and to the ring.

3. A device of the class described comprising a receptacle having a discharge and a valve seat surrounding the discharge, a valve 85 engaging said seat and having an upwardly directed stem, an annular screen member supported at its outer edge by the receptacle and spaced above the valve seat, and a central support connected to the inner edge of 90 the screen and provided with a guide aperture to receive the valve stem.

4. A device of the class described comprising a receptacle having a transverse dia- 95 phragm provided with a discharge and a valve seat surrounding the discharge, a valve 100 engaging said seat and having an upwardly directed stem, an annular screen member supported at its outer edge upon the diaphragm and spaced above the valve seat, a central support connected to the inner edge 105 of the screen and provided with a guide aperture to receive the valve stem, a stay ring engaging the inner edge of the screen material, a stay bar extending over the central support, and fastening devices through the stay bar, central support, stay ring, and screen member.

5. A device of the class described comprising a receptacle having a transverse dia- 110 phragm provided with a discharge and a valve seat surrounding the discharge, a valve 115 engaging said seat and having an upwardly directed stem, an annular screen member supported at its outer edge upon the dia- 120 phragm and spaced above the valve seat, a central support connected to the inner edge of the screen and provided with a guide aperture to receive the valve stem, a stay bar extending over the central support and con- 125 nected to the support and to the diaphragm, and a guide member attached to the stay bar and through which the valve stem is slidably disposed.

In testimony whereof I affix my signature. 125
CHARLES B. DOOLIN. [L.S.]
